Primary Examiner — John Windmuller*Assistant Examiner* — John R Yeh(57) **CLAIM**

The ornamental design for a dispenser, as shown and described.

DESCRIPTION

FIG. 1 is a perspective top view of the dispenser;
 FIG. 2 is a front elevation view of the dispenser;
 FIG. 3 is a rear elevation view of the dispenser;
 FIG. 4 is a left side elevation view of the dispenser;
 FIG. 5 is a right side elevation view of the dispenser;
 FIG. 6 is a top elevation view of the dispenser;
 FIG. 7 is a bottom elevation view of the dispenser; and,
 FIG. 8 is an exploded perspective top view of the dispenser. The text and graphics in FIG. 7 are shown in broken lines for illustrative purposes only and form no part of the claimed design.
